CLAIM

The ornamental design for an electrical apparatus having a square plan view, as shown and described.

DESCRIPTION

FIG. 1 is a rear, left side perspective view of an embodiment of the electrical apparatus having a square plan view.

FIG. 2 is a left side elevational view thereof.

FIG. 3 is a top plan view thereof.

FIG. 4 is a bottom plan view thereof; and,

FIG. 5 is a bottom, left side perspective view thereof. Notably regarding this embodiment of the electrical apparatus having a square plan view, the two stoppers on the respective ends of the casing/housing are flush with the casing/housing.

Regarding FIGS. 1 and 3, the additional dashed lines inside each of the pairs of rectangular electrical outlet openings represent tamper resistant layers in the respective rectangular electrical outlet openings.

The dashed lines in the drawings depict environmental subject matter only and form no part of the claimed design.
